UNITED STATES PATENT OFFICE.

GAETANO ALBANESE, OF NEW YORK, N. Y.

PERMUTATION-LOCK.

1,158,152.

Specification of Letters Patent. Patented Oct. 26, 1915.

Application filed January 19, 1915. Serial No. 3,065.

To all whom it may concern:

Be it known that I, GAETANO ALBANESE, a subject of the King of Italy, and a resident of the city of New York, borough of Manhattan, in the county and State of New York, have invented a new and Improved Permutation-Lock, of which the following is a full, clear, and exact description.

The object of the invention is to provide 10 a new and improved permutation lock more especially designed for use on doors, tills and other devices, and arranged to hold the bolt normally in withdrawn position, say, during the day, and to allow of moving the 15 bolt into shot-out or locking position during the night and to hold the bolt in this position without danger of an unauthorized person being enabled to retract the bolt.

In order to produce the desired result, use 20 is made of a spindle provided at its outer end with a knob for turning the spindle, a cam arm fixed on the inner end of the spindle and provided at one end with a slot and at the other end with a cam, a slidable bolt 25 provided with a pin engaging the said slot, a series of tumblers provided at their peripheral faces with notches adapted to register with each other, and a sliding yoke having a cross bar extending across the peripheral 30 faces of the said tumblers and adapted to drop into the said notches at the time the notches are in transverse alinement, the said bar being controlled by the said cam.

A practical embodiment of the invention 35 is represented in the accompanying drawings forming a part of this specification, in which similar characters of reference indicate corresponding parts in all the views.

Figure 1 is a rear face view of a permutation lock with the bolt in withdrawn position and the casing cover removed; Fig. 2 is like view of the same with the bolt shot out and with part of the cam arm broken out; Fig. 3 is a similar view of the same with the 45 yoke in raised position; Fig. 4 is a rear face view of the bolt and yoke with the spindle and hubs of the tumblers shown in section; Fig. 5 is a cross section of the permutation lock on the line 5—5 of Fig. 1; Fig. 6 is a 50 face view of the dials with the spindle shown

in section on the line 6—6 of Fig. 5; Fig. 7 is a face view of the same with the dials in set position; Fig. 8 is a face view of one of the dials; and Fig. 9 is a side view of the swing arm for resetting the tumblers to a 55 different combination.

The casing A of the permutation lock is secured to the inner face of a door B, and the said casing is provided with a removable cover A' and with a bearing extending transversely through the door to the front face thereof, as plainly shown in Fig. 5. In the casing A is mounted to slide a bolt C provided with a transversely extending pin C' projecting into a Z-shaped slot D' formed in 60 the lower end of a cam arm D secured on the inner end of a spindle E extending centrally through the bearing A' and provided at its outer end with a knob E' under the control of the operator for turning the spindle E with a view to impart a swinging motion to the cam arm D. When the knob E' is turned in one direction, as indicated by the arrow a' in Fig. 1, then the bolt C is shot outward by the action of the arm D on the 65 pin C', and when the knob is turned in the opposite direction then the bolt C is retracted.

The upper end of the cam arm D is provided with a cam D² adapted to engage the 70 under side of a transverse bar F forming part of a yoke F' mounted to slide up and down in the casing A. The bar F is pressed on by a spring G held in the casing A and the bar F extends transversely across the 75 peripheral faces of a series of tumblers H, H', H² and H³, each provided at its peripheral face with a notch H⁴. Normally the bar F rides on the peripheral faces of the tumblers H, H', H² and H³, but the bar is adapted 80 to drop into the notches H⁴ whenever the same are in transverse alinement one with the other and in top position, as indicated in Figs. 1, 2 and 5. The lower end of the yoke F' is provided with a pin F² adapted 85 to engage either of the shoulders C² or C³ formed on the lower end of the bolt C, as hereinafter more fully described. The tumblers H, H', H² and H³ are adapted to be turned individually by dials I, I', I² and I³ 90

100

arranged one behind the other and centrally relative to the spindle E intermediate the knob E' and the front face of the bearing A². On each of the tumblers H, H', H² and H³ is 5 pivoted a dog H⁵ (see Fig. 2) engaging one of a series of notches H⁶ formed in the peripheral face of a resetting disk H' having a hub H⁸, the hubs of the several disks for the tumblers H, H', H², H³ extending transversely and having at their forward ends. 10 fixed thereto, the several dials I, I', I² and I³.

As shown in Fig. 5, the hub H⁸ of the disk H' for the first tumbler H is mounted loosely on the spindle E while the other hubs are mounted one within the other so that the tumblers H, H', H², H³ can be turned independently one relative to the other on turning the corresponding dial I, I', I² or I³. Each of the dials I, I', I² and I³ 15 is provided with a series of numerals, letters of the alphabet or other indicating characters I⁴, preferably consecutive numbers from 1 to 10 and spaced apart on each dial with a groove I⁵ between adjacent characters so that the latter appear raised to enable the user to readily grip any one of the dials with a view to turn the same until the indicating characters forming the combination at the time register with a mark J 20 on the face of the door, as plainly indicated in Fig. 7. It is understood that when the dials are set to the combination the notches H⁴ of the several tumblers H, H', H² and H³ are in transverse alinement one with the 25 other and on top of the tumblers directly in register with the bar of the yoke F', so that the latter can engage the said registering notches and thereby hold the tumblers against movement for the time being.

40 The operation is as follows: When the dials I, I', I² and I³ have been set to the proper combination then the yoke bar F is moved into engagement with the registering notches H⁴ by the action of the 45 spring G, and the pin F² on the yoke F' is below the shoulders C², C³ so that the operator on turning the knob E' can move the bolt C outward into locking position whenever it is desired to lock the door. It will 50 be noticed that when the knob E' is turned in the direction of the arrow a' the pin C' is pushed forward by the wall at the middle portion of the slot D' and during this movement of the arm D the pin travels in the 55 vertical portion of the slot D' until it finally reaches the lower portion of the said slot (see Fig. 2) at the time the bolt C has been completely shot out into engagement with the keeper (not shown) on the door casing. At 60 this time the cam D² engages the bar F so that on a further turning of the knob E' in the direction of the arrow a' the bar F is raised against the tension of the spring G

and is thus moved out of engagement with the registering notches H⁴. When the bar F and consequently the yoke F' is raised the pin F² moves into engagement with the shoulder C³ (see Fig. 3), and at this time the operator turns one, two or all of the dials I, I', I² and I³ to move the corresponding notches H⁴ out of register with the bar F, so that on releasing the knob E' the bar F rests on the peripheral faces of the tumblers H, H', H² and H³. It will be noticed that the bolt C is now held against return movement by the pin F² abutting against the shoulder C³, and the bar F is held against downward movement as it rests on the peripheral faces of the tumblers H, H', H² and H³. When it is desired to 70 retract the bolt C it is first necessary for the operator to turn the dials I, I', I² and I³ until the proper combination is in register with the mark J so that the bar F moves into engagement with the registering notches H⁴ by the action of the spring G. During this downward movement of the bar F and the yoke F' the pin F² moves out of engagement with the shoulder C³ so that the operator on turning the knob E' can retract the 75 bolt by the action of the arm D.

The tumblers H, H', H² and H³ can be reset for any desired combination to suit the fancy of the user and for this purpose the following arrangement is made: On the 80 upper end of the arm D is formed a second cam D³ extending in an opposite direction to the cam D² and adapted to engage and lift the bar F on turning the knob E' in the inverse direction of the arrow a'. When 85 this takes place the pin F² engages the shoulder C² to hold the bolt C in retracted position during the resetting operation. Each of the dogs H⁵ is pressed on by a spring H⁹ to hold the same in engagement 90 with the corresponding notch H⁶, as shown in Fig. 2, and the free end of the said dog H⁵ is adapted to be engaged by a swing arm K fulcrumed on the casing A and provided at its free end with a number of 95 prongs K', each adapted to press on the free end of a corresponding dog H⁵. The swing arm K is pivotally connected with a push button K² extending through one side of the 100 wall of the casing A, and the push button is pressed on by a spring K³ to normally hold the push button K² in outermost position and the swing arm K out of the path of the dogs H⁵. When it is desired to reset 105 it is only necessary for the operator to press the push button K² inward so that the swing arm K imparts a simultaneous swinging movement to the several dogs H⁵, which now are all in alinement with each other owing 110 to the position of the tumblers H, H', H² and H³. The operator can now turn any 115

one or all of the dials I, I', I² and I³ to move any desired combination of characters into register with the mark J, and when this has been done the operator releases the push 5 button K² and consequently the dogs H⁵ to allow the latter to engage the corresponding notches H⁶ in the disks H⁷. After the resetting has been completed the knob E' is released so that the several parts assume the 10 position shown in Fig. 1. The bolts C can now be shot out whenever it is desired to do so, in the manner above described. The rear end of the bar F is adapted to engage a notch in the plate L attached to the casing A to give the desired support to the said bar F 15 when in engagement with the notches H⁴ of the several tumblers.

Having thus described my invention, I claim as new and desire to secure by Letters 20 Patent:

1. A permutation lock, comprising a spindle provided at its outer end with a knob for turning the spindle, a cam arm fixed on the inner end of the spindle and provided 25 at one end with a slot and at the other end with a cam, a slideable bolt provided with a pin engaging the said slot, a series of tumblers provided at their peripheral faces with notches adapted to register with each 30 other, and a vertically movable sliding yoke having a cross bar extending across the peripheral faces of the said tumblers and adapted to drop into the said notches at the time the notches are in transverse alinement, 35 the said bar being controlled by the said cam.

2. A permutation lock, comprising a spindle provided at its outer end with a knob for turning the spindle, a cam arm fixed 40 on the inner end of the spindle and provided at one end with a slot and at the other end with a cam, a slideable bolt provided with a pin engaging the said slot, a series of tumblers provided at their peripheral faces with notches adapted to register with each other, a sliding yoke having a cross bar extending across the peripheral face of the said tumblers and adapted to drop into the said notches at the time the 45 notches are in transverse alinement, the said bar being controlled by the said cam, a shoulder on the said bolt, and a pin on the said yoke adapted to engage the said shoulder on lifting the yoke at the time the bolt 50 is shot out.

3. A permutation lock provided with tumbler disks each having a notch at the peripheral face, a resetting disk for each tumbler disk and provided with a hub on 55 which the corresponding tumbler disk is mounted to turn loosely, each resetting disk having a plurality of notches on its peripheral face, a dog fulcrumed on each

tumbler disk and engaging one of the notches on the resetting disk, springs for 65 normally holding the dogs in engagement with the said notches, a swing arm provided at its free end with spaced prongs adapted to engage the free ends of said dogs, a push button pivotally connected with the swing 70 arm for imparting a swinging motion to the said swing arm, and a spring pressing on the push button to normally hold the swing arm out of the path of the said dogs.

4. A permutation lock, comprising a spindle having a knob at its outer end, a cam arm fixed on the inner end of the said spindle and provided at one end with a Z-shaped slot and at its other end with a cam, a slideable bolt having a pin projecting into the 75 said slot, the bolt having a shoulder, a series of tumblers arranged centrally on the said spindle and each having a notch at its peripheral face, means for turning the said tumblers, and a yoke mounted to slide and 80 having a bar extending transversely across the peripheral face of the said tumblers to engage the said notches when the latter are in alinement, the said bar being adapted to be engaged by the said cam, the said yoke 85 having a pin adapted to engage the said bolt shoulder.

5. A permutation lock comprising a spindle provided at its outer end with a knob for turning the spindle, a cam arm fixed on 95 the inner end of the spindle and provided at one end with a slot and at the other end with a cam, a slideable bolt having an elongated opening through which the spindle passes, the said bolt being provided with a pin engaging the said slot in the cam arm, a series 100 of tumblers provided at their peripheral faces with notches adapted to register with each other, a sliding yoke having vertical guided movement in the casing, the said 105 yoke having a transverse bar extending across the peripheral face of the tumblers, a spring pressing on said bar, the said bar being adapted to engage the said notches in the tumblers when the notches are in transverse alinement, a shoulder on the said bolt, a pin on the said yoke adapted to engage the 110 said shoulder when the yoke is in raised position to hold the bolt in locked position, the cam on said cam arm engaging the said 115 bar to lift the yoke against the tension of the said spring.

6. A permutation lock provided with a spindle, a cam arm fixed on the spindle and provided at one end with a slot, a slideable 120 bolt provided with a pin engaging the said slot, the bolt being adapted to be actuated by the cam arm, a series of tumblers each provided with a notch in its peripheral face, a sliding yoke having a bar for engaging the 125 said notches when the latter are in trans-

verse alinement, the said bolt being adapted to be retracted when the bar is in engagement with said notches, a cam on the said cam arm for raising the said yoke and bar when the bolt is in retracted position, a shoulder on the said bolt, a pin on the said yoke adapted to engage the said shoulder to hold the bolt in retracted position, resetting disks for the tumblers normally locked thereto, and means for releasing the re-

setting disks to change the combination when the bolt is held in the retracted position.

In testimony whereof I have signed my name to this specification in the presence of 15 two subscribing witnesses.

GAETANO ALBANESE.
